US00D618231S

(12) **United States Design Patent**
Fahrendorff et al.

(10) **Patent No.:** **US D618,231 S**
(45) **Date of Patent:** **** Jun. 22, 2010**

(54) **HANDHELD ELECTRONIC DEVICE SKIN**

(75) Inventors: **Anders Fahrendorff**, Ottawa (CA);
Roman Peter Rak, Waterloo (CA);
Archer Chi Kwong Wun, North York (CA); **Alina Claudia Oprea**, Waterloo (CA)

(73) Assignee: **Research In Motion Limited**, Waterloo (CA)

(**) Term: **14 Years**

(21) Appl. No.: **29/344,564**

(22) Filed: **Sep. 30, 2009**

(51) **LOC (9) Cl.** **14-03**

CLAIM

We claim the ornamental design for a handheld electronic device skin, as shown and described.

DESCRIPTION

FIG. 1 is a front perspective view of a handheld electronic device skin;

FIG. 2 is a back perspective view of a handheld electronic device skin;

FIG. 3 is a front elevation view thereof;

FIG. 4 is a rear elevation view thereof;

FIG. 5 is a right elevational view thereof;

FIG. 6 is a left elevational view thereof;

FIG. 7 is a top plan view thereof; and,

FIG. 8 is a bottom plan view thereof.
